United States Patent Office.

ROBERT HENEAGE AND F. W. BREED, OF BUFFALO, NEW YORK.

Letters Patent No. 78,206, dated May 26, 1868.

RAILROAD-CAR VENTILATORS.

The Schedule referred to in these Letters Patent and making part of the same.

TO ALL WHOM IT MAY CONCERN:

Be it known that we, ROBERT HENEAGE and F. W. BREED, of the city of Buffalo, in the county of Erie, and State of New York, have invented certain new and useful Improvements in Method of Ventilating Railroad-Coaches; and we do hereby declare that the following is a full and exact description thereof, reference being had to the accompanying drawings, making part of this specification, in which—

Figure I is a side elevation of a locomotive-tender and one coach provided with our improvements.

Figure II is a plan of the smoke-stack and the funnel induction-end of the air-tube.

Figure III is an enlarged and partially sectional view of the pipe-coupling between the cars.

Figure IV is a view of one of the ends or contiguous faces of the said coupling.

Figure V is an enlarged vertical section of the wind-wheel and suction-screw, for withdrawing the vitiated air.

Figures VI and VII are horizontal sections, made respectively on lines *xx* and *yy* in Fig. V.

Our invention consists—

First, in the arrangement, along the top of the cars, of an air-pipe, with two funnel induction-mouths at the front of the locomotive, on each side of the smoke-stack, when the said pipe is provided with a flexible coupling between the cars, and with branch-pipes descending and opening on each side into the car, where they are provided with stop-cocks or registers, within convenient reach of the passengers, for regulating the ingress of the air.

Second, the coupling for the said air-pipe, when constructed, so that each half of the same can be used indifferently as a male or female, as may be required.

Third, the construction and arrangement of a device for exhausting the vitiated air from the car, composed of a wind-wheel, operating a suction-screw, and a register for controlling the exhaust produced thereby.

Fourth, the combination of the last device with the aforesaid arrangement for supplying fresh air, when the whole is employed in ventilating railroad-cars, as will hereafter be fully set forth.

Fifth, the arrangement of a valve or stop-cock in the air-pipe at each end, for closing the same when the car forms the last one of the train.

In the drawings, A B C represent a locomotive, tender, and a coach of a railroad-train; D, an air-pipe, arranged on top of the cars, being divided at the front end into two branches, D¹ D¹, passing on each side of the smoke-stack, and provided with funnel-shaped mouths, D² D², for receiving and concentrating the air, which, in connection with the velocity of the train, causes a strong draught through the pipe. D³ is a flexible portion of the pipe between the cars, which is provided with a coupling, E, of the peculiar construction hereafter described. Over each coach to be supplied with air from the pipe D extend transversely small branch-pipes *d d*, on each side, which pass into and descend the sides of the cars to a suitable distance, for discharging the air into the car, stop-cocks or registers, *d'*, being arranged at their extremities, by which the ingress of the air can be conveniently regulated by the passengers. The pipe D, at each end of the coaches, is provided with a check or other valve, *a*, so that the rear end of the pipe of the last coach of the train can be closed, so as to prevent the escape of air at that point, and thereby compel the air to descend the branch-pipes *d*.

The coupling E is required to be so constructed that both halves may be used indifferently as a male or female; or, in other words, the coaches are required to be so constructed that either end of each can be connected with either end of any other car, and, consequently, the halves of the coupling for the pipe must possess the same adaptability of engagement. For this purpose, we construct each half of the coupling with a face-plate, *e*, provided with ears, *e' e'*, on opposite sides, from which extend, parallel with the pipe, sleeves *e'*, in which slide the locking-bolts *f*. The ear-portions of the face-plates *e* have rectangular or elongated openings, *i*, through which pass the correspondingly-formed heads *f'* of the sliding bolt of the other portion of the coupling, the two plates being fastened together by partially turning the bolts, (which the enlarged socket of the sleeve permits,) so that the lugs of the head will engage with the sides or shoulders of the opening, as clearly shown in the sectional part of Fig. III. The bolts *f* are provided with thumb-levers, *g*, or equivalent, for turning them, and with a pin, *f'*, projecting from each, which fits and slides in an L or longitudinal and transverse slot, *m*, in the

sleeve. The transverse portion of the slot is preferably made so as to incline away from the joint of the coupling, so that, in turning the bolt in locking the parts together, the inclination of the slot will tend to draw the two faces of the coupling more firmly together.

It is evident that only two of the four bolts of the coupling are in use at the same time, the other two being drawn back out of the way, as shown at the left in Fig. III.

The features of our improvements are designed to furnish, at all times, an ample supply of pure air, which, entering the pipe at the very front end of the locomotive, must be entirely free of the dust, cinders, and smoke which always contaminate, more or less, the air which enters the cars directly through the windows or other apertures.

By multiplying the branch-pipes d , the supply for every seat, or every two seats, may be entirely under the control of its or their occupants, who can, by means of the registers d' , adapt the draught to their different requirements. Any person who has experienced the alternative of breathing the close and vitiated air of a car, or of enduring the equally unpleasant draught of air, dust, and cinders, will fully appreciate this feature of our invention.

The arrangement shown for facilitating the withdrawal of the vitiated air consists of a vertical cylindrical case, H , on top of each coach, in which are arranged, on the same shaft, a wind-wheel, I , and suction-screw or fan, J , which is operated by the wind-wheel.

The case H is pivoted in a step, as shown, or supported in some other suitable way, so as to be capable of being turned by the vane l , attached to one side.

The side opposite the vane is left open, as shown, and is provided with two diverging wings, $n n$, to collect the wind, and direct it to the wheel, a suitable aperture for its escape being left on the opposite side, as shown at o , Fig. VI.

Below the wind-wheel is arranged a floor or diaphragm, dividing the case; below which is the compartment in which the screw revolves. A passage, s , is formed through the roof of the car, opening up into the bottom of this latter compartment, which passage is controlled by a register, p . An aperture, g , is provided in the case, H , above the screw, as an outlet for the vitiated air which is drawn up through the passage s by the action of the screw.

By means of this arrangement, a draught through the passage s , of greater or less force, can always be produced, removing the vitiated and impure air from the car with great facility. In cold weather, the opening can be partially or entirely closed by the register p , as comfort or other circumstances may require, while in summer, during the extreme hot weather, a constant current of pure fresh air can always be maintained through the car by means of this arrangement, combined with the one previously described, thereby promoting the comfort as well as the health of the passengers.

In addition to the advantages already enumerated, the employment of our improvements will be of great importance in protecting the clothes and persons of passengers from the most disagreeable and deleterious effects of dust and lamp-black.

This will not only effect a great saving in the line of clothing, but will also dispense with, to a great extent, the necessity of a change in garments of a passenger, as he emerges from a car, before he is in a fit plight to appear in polite society.

The inconvenience that will thus be avoided, all must appreciate.

What we claim as our invention is—

1. The coupling E , when constructed and operating substantially in the manner shown and described.
2. The pivoted case H , provided with wings $n n$ and vane l , in combination with the wind-wheel I , screw or fan J , and register p , the whole arranged and operating substantially as and for the purpose set forth.
3. The combination of the two devices, herein described, for supplying pure air and withdrawing the impure air, from railroad-coaches, substantially as set forth.

ROB'T HENEAGE,
F. W. BREED.
